PUMP

Robert G. Huling, Battle Creek, Mich., assignor to
S. H. Leggitt Company, Marshall, Mich., a corporation of Michigan

Filed Mar. 7, 1967, Ser. No. 6,106

Term of patent 14 years

(Cl. D65—1)

The dominant features of my design reside in the portions shown in solid lines.

I claim:

The ornamental design for a pump, as shown and described.
